UNITED STATES PATENT OFFICE.

EINAR OLAÜS IVERSEN, OF CHICAGO, ILLINOIS.

CARPENTER'S SQUARE.

No. 862,166.

Specification of Letters Patent.

Patented Aug. 6, 1907.

Application filed December 28, 1906. Serial No. 349,849.

To all whom it may concern:

Be it known that I, EINAR OLAÜS IVERSEN, a citizen of the United States, residing at Chicago, in the county of Cook and State of Illinois, have invented certain new 5 and useful Improvements in Carpenters' Squares, of which the following is a specification.

My invention relates to tools and has special reference to carpenters' squares. Its chief objects are to provide a tool of that class so constructed that it can be readily 10 taken apart thus rendering it more portable and convenient for carrying and permitting it to be placed in an ordinary box or bag.

Further objects of my improvement are to provide means for rendering the joints, which must necessarily 15 enter into any separable construction, accurate and durable, and to furnish a connecting member of solid construction thus giving strength and firmness to the joint.

Further objects of my invention are to provide a 20 tongue and groove joint at the line of junction of the blades in order to prevent lateral displacement which would tend to destroy the efficiency of the tool; and to furnish means for securing the parts together when assembled in order to prevent accidental displacement.

25 I accomplish the above mentioned and other minor objects by the device illustrated in the accompanying drawing which forms a part of this specification and in which:—

Figure 1 is a side view of my improved separable 30 square with the parts assembled; Fig. 2 is a fragmentary view of the reverse side showing the retaining screws; Figs. 3 and 4 are fragmentary views enlarged of the joint ends of the blades, and Figs. 5 and 6 are enlarged sectional views of Fig. 1.

35 Referring to the drawing, 7 indicates the large blade and 8 the small blade of a carpenter's square. These blades are each formed of a separate piece, the contiguous ends being cut on a bevel so that when joined they will form a true right angle, the line of junction 9 extending from the inner to the outer angle. The blades are firmly held in apposition by a connecting piece or union 10 which has two arms 11, 12, formed at right angles with each other. The larger of the arms 11 is received into a groove or gain 13 cut in one side of the 40 large blade 7, the margins 14 being undercut, or dovetailed to correspond with the dovetailed edges 14 of the said arm 11 of the union. The margins of the smaller arm 12 are similarly dovetailed to engage a like groove 15 cut in the side of the small blades 8. The ends 16

45 of the union are preferably rounded and the extremities of the gains 13, 15, are formed to correspond, this shape giving a more accurate fit and being more easily manufactured than when the ends are left square.

The gains are preferably made of a depth equal to about half the gage of the blades and the union formed 55 of a corresponding thickness so that the latter will be flush with the blade surfaces.

As the blades of the square are proportionally very much longer than their width, the strain upon the dovetailed margins of the union will be correspondingly 60 great, and there will be more or less tendency to give in a joint which is frictionally held against such a powerful leverage. I overcome the tendency to lateral displacement by forming a tongue and groove joint where the inclined faces of the blades come together to form the 65 junction 9. The tongue 17 of the joint is formed on the joint face of the small blade and a corresponding groove 18 is provided in the opposing joint face of the large blade, although this order may be reversed without changing the result.

70 The blades are readily assembled by sliding the arms of the union 10 into their respective gains until the tongue 17 engages the groove 18 and the blades are in close apposition at the juncture 9.

To prevent the blades from working loose when subjected to hand usage by the slipping of the union in its gains, I provide locking screws 19 which pass through the blades and engage threads in the arms of the union 75 the holes for the screws in the blades being countersunk so that the heads are flush with the face of the tool. 80

Having thus described my invention what I claim as new and desire to secure by Letters Patent, is:—

1. A separable square including a plurality of blades, a right-angled connecting member separable from said blades, and a tongue and groove beveled joint at the junction of 85 the blades.

2. A carpenter's square including a plurality of separable blades, a right-angled connecting member separable from said blades, a tongue and groove beveled junction between the ends of the blades, and means for securing the 90 parts when assembled.

3. A separable square including a plurality of detachable blades each blade provided with a lateral gain, a connecting member adapted to engage the said gain in each blade, a tongue and groove junction between said blades, 95 and means for locking the blades in engagement with said connecting member.

4. A square including a plurality of separable blades each blade provided with a lateral gain having undercut margins, a right angled union having dovetailed edges 100 adapted to engage said lateral gains, a tongue formed in the end of one blade and adapted to engage a groove formed in the other blade and means for locking the parts when assembled.

In testimony whereof I affix my signature in presence of 105 two witnesses.

EINAR OLAÜS IVERSEN.
